BY Victor J. Evans & Co.

ATTORNEY

UNITED STATES PATENT OFFICE

2,007,846

WRENCH

Clarence E. Brady, Morning View, Ky.

Application June 4, 1934, Serial No. 729,015

1 Claim. (Cl. 81—137)

The invention relates to a wrench and more especially to a quick-adjusting wrench known as the "sliding jaw" type.

The primary object of the invention is the provision of a wrench of this character, wherein the sliding jaw carries a hand actuated slidably adjustable latching bolt which permits of the locking of the sliding jaw with relation to the stationary jaw for the clamping of a piece of work, the sliding adjustment of the bolt being to permit close adjustment of the sliding jaw with relation to the work and also permits of the quick and easy latching and unlatching of said sliding jaw at the will of the user of the wrench.

Another object of the invention is the provision of a wrench of this character which is extremely simple in its construction, thoroughly reliable and effective in its purpose, strong, durable, highly practical, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claim hereunto appended.

In the accompanying drawing:

Figure 1 is a side elevation of a wrench constructed in accordance with the invention and being partly in section with the latching bolt in latching position.

Figure 2 is a view similar to Figure 1 showing the latching bolt in releasing position.

Figure 3 is an edge elevation.

Figure 4 is a section on line 4—4 of Figure 1.

Similar reference characters indicate corresponding parts throughout the several views in the drawing.

Referring to the drawing in detail, the wrench comprises a shank 5 having formed therefrom at one end the handle 6 and at the other end is provided a stationary jaw 7. Upon the shank 5 is carried the slideable jaw 8, it being formed with a sleeve-like portion 9 which embraces the shank 5 for the slideable connection thereof.

The inner longitudinal edge of the shank 5 is provided with a toothed rack 10, while formed in the sliding jaw parallel with the rack and on the side next thereto is a socket 11 which opens through the outer end edge 12 of said sliding jaw and accommodates a slideable and rotatable latching bolt 13. The outer end of the bolt 13 is formed with a curved latching tip or terminal 14 adapted

for selective engagement between any of the teeth of the rack 10 so as to lock the sliding jaw 8 in adjusted position.

The sliding jaw 8 has formed therein and intersecting the socket or way 11 for the bolt 13 a recess 15 for accommodating a turning sleeve 16, the latter receiving the said bolt 13 and being fitted with a set screw 17 which binds against the bolt to prevent displacement by sliding movement in the socket 11 on adjustment in the use of said 10 set screw.

The handle end of the shank 5 is formed to provide a screw driver tip or bit 18 so that the wrench can be utilized as a screw driver, or prying tool.

In the use of the wrench, assuming that the bolt 13 is in latching position with the rack 10 and it is desired to adjust the sliding jaw 8, the turning sleeve 16 is rotated in the recess 15, thus throwing the tip or terminal 14 of the bolt 13 to a disengaged position with the rack 10 and thus freeing the sliding jaw 8 so that it can be moved to a piece of work to be held between the stationary jaw 7 and sliding jaw 8. Thereupon, the turning sleeve 16 is rotated to bring the tip or terminal 14 of the bolt 13 into engagement with the rack 10 and thus locking the sliding jaw related with the work. If accurate adjustment is desired the set screw 16 can be loosened and by sliding the sliding jaw 8 with relation to the bolt 13 the said sliding jaw can be brought into close contact with the work to be operated upon. Thereafter, the set screw 17 is worked home against the bolt to hold the same fixed in the sliding jaw.

From the foregoing it is believed that the advantages and novel features of the invention will be readily understood and, therefore, further detailed description is deemed unnecessary and omitted.

What is claimed is:

In a wrench, a sliding jaw, a toothed rack, a fixed jaw on the rack and cooperating with the sliding jaw, a turning sleeve fitted in the sliding jaw, a latch bolt slidably fitted in said turning sleeve and providing the journal therefor in said sliding jaw, a keeper tip turned from the bolt and engageable with the rack beyond the sliding jaw, and means for making fast the bolt in said sleeve for the turning of the bolt therewith to bring its tip into and out of engagement with the rack,

CLARENCE E. BRADY.
